[57] CLAIM

The ornamental design for a liner for vehicle cargo space, as shown and described.

DESCRIPTION

FIG. 1 is a perspective view of a liner for vehicle cargo space embodying my new design;

FIG. 2 is a side elevational view thereof;

FIG. 3 is an elevational view thereof showing the side opposite that shown in FIG. 2;

FIG. 4 is a rear elevational view thereof;

FIG. 5 is a front elevational view thereof; and

FIG. 6 is a top plan view thereof, the bottom not being visible during normal use of the cargo liner.

*Fig. 1.**Fig. 2.**Fig. 3.*Fig. 4.

Fig. 5.

Fig. 6.
